United States Patent Office.

LYMAN M. SEVERANCE, OF DIXON, ILLINOIS.

Letters Patent No. 67,596, dated August 6, 1867.

IMPROVEMENT IN PLATFORM-SCALES.

The Schedule referred to in these Letters Patent and making part of the same.

TO ALL WHOM IT MAY CONCERN:

Be it known that I, LYMAN M. SEVERANCE, of Dixon, in the county of Lee, and State of Illinois, have invented a new and useful Improvement in Platform-Scales; and I do hereby declare and make known that the following is a full, clear, and exact description thereof, reference being had to the accompanying drawings, and the letters and figures marked theron, which form part of this specification.

To enable those skilled in the art to understand how to construct and use my invention, I will proceed to describe its construction and operation with particularity, making reference, in so doing, to the aforesaid drawings, in which—

Figure 1 represents a plan view of the system of levers beneath the platform, which is removed.

Figure 2 is a side view of the same seen from the rear, and

Figure 3 is a similar view seen from the front.

In said drawings the same letters of reference represent the same parts of my invention in the several figures.

A represents the frame and enclosure within which the levers and superincumbent platform are arranged. B represents two heavy cross-timbers, arranged at each end of the frame, which rest upon the levers D E, as hereinafter described, upon which the longitudinal beams C are secured, the platform being arranged upon the said sleepers C C, and thus resting upon the aforesaid levers D E. These levers, as shown in the drawings, are arranged in pairs, one pair being longer than the other, extending from the four corners of the frame and platform to a point back of the platform and midway from each end, where they are connected with the rod F, which is attached at its upper end to the scale-beam G. These four levers are each secured to the said rod F by separate links or connections l, as shown in fig. 2, so that each lever acts upon said rod and scale-beam, wholly independent of and unimpeded by the others. The ends of the levers D D, at the corners of the platform, are attached to the rigid framework of the apparatus by a staple and clevis arrangement, as shown in the drawings at a b, while the like ends of the levers E are similarly attached to the immovable frame, as shown in the drawings at m. The platform is suspended upon the levers D by means of staple and clevis connections, as shown c d, the staples being attached to the aforesaid cross-timbers B, and upon the levers E at the points n, by a similar arrangement, as shown in fig. 2.

Although I regard the specific modes herein described of connecting the levers to the frame, the platform, and the rod F as being very superior in point of practicability, still said connections may be made in any other suitable manner.

The points c and n, where the platform rests upon said levers D E, are taken in such manner as that the proportion between the respective arms shall be as follows: The length of the arm l c is to the length of the arm a c in the lever D as the length of the arm l n is to the length of the arm m n in the levers E, so that a given weight upon the platform shall act uniformly at the point l upon all the four levers, and with same effect upon the scale-beam.

By this arrangement of the levers they can be arranged beneath the platform in a small space, so as to render it wholly unnecessary to construct a pit beneath to contain the levers or system of levers, which is required with other kinds of scales, the surface of the platform not being necessarily more than about fifteen inches above the level of the ground, so that teams can easily be driven upon the platform by simply arranging inclines at each end.

Having described the construction and operation of my invention, I will specify what I claim, and desire to secure by Letters Patent:

I claim the combination of the four levers D D E E, when arranged with respect to the platform and its permanent frame and the rod F, substantially in the manner and for the purposes herein specified.

Witnesses:

WILLIAM J. CARPENTER,
JEROME W. HOLLINBECK.

LYMAN M. SEVERANCE.
